FIG. 1.

FIG. 2.

FIG. 3.

FIG. 1 is a perspective view of a patio cover corner adornment, showing our new design, and illustrating the outside three faces thereof taken along a line toward the corner of the intersection of the said three faces;

FIG. 2 is a perspective view of the inside of our corner adornment taken along the same line as in FIG. 1 but from the opposite end of said line; and

FIG. 3 is a side elevational view of our corner adornment showing the inside thereof, and a mirror image of said FIG. 3 would also show the inside viewed 90 degrees disposed therefrom, the adornment being symmetrical about a plane normal to and intersecting the vertical edge of the two side faces illustrated in FIG. 1.

We claim:

The ornamental design for a patio cover corner adornment, as shown and described.
